UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP CONSISTING OF FRANCIS E. MYERS AND PHILIP A. MYERS.

POWER ATTACHMENT FOR PUMPS.

1,213,935.

Specification of Letters Patent. Patented Jan. 30, 1917.

Application filed November 24, 1915. Serial No. 63,175.

To all whom it may concern:

Be it known that I, PHILIP A. MYERS, a citizen of the United States, residing at Ashland, in the county of Ashland and 5 State of Ohio, have invented certain new and useful Improvements in Power Attachments for Pumps, of which the following is a specification, reference being had therein to the accompanying drawing.

10 This invention relates to a power-attachment or jack for pumps. In power-attachments now in use the attachment is either rigidly fixed to the pump-stand permanently or constitutes a jack which rests 15 upon the floor adjacent thereto.

The primary object of my invention is to provide a power-attachment which may be readily attached to and detached from a pump-stand, the nature of the attaching 20 devices enabling the stand to satisfactorily support the attachment while the apparatus is in use.

It is a further object of the invention to provide a device which will be satisfactory 25 in light work.

It is a further object of my invention to provide a device which can be attached to a pump-stand in a most economical and convenient manner, simple in all its parts and 30 at a low cost.

In the accompanying drawings, Figure 1 is a side elevation of the device; Fig. 2 is a rear elevation thereof; Fig. 3 is an enlarged side elevation with parts not shown; 35 Fig. 4 is a rear elevation of the parts shown in Fig. 3; and Fig. 5 is a cross section on the line 5—5 of Fig. 3, looking in the direction of the arrows.

The drawings disclose one embodiment of 40 the invention in which 1 indicates the pump stand. Cast integral with this pump stand or fixed to it in any suitable manner are two pairs of spaced lugs indicated at 2 and 3. These spaced lugs are adapted to be 45 engaged by the attachment indicated generally at 4. This attachment 4 is here shown as a pair of bearings 5 and 6 spaced vertically above each other. It will be observed from the drawings that I have shown 50 the lugs as attached to or carried by the pump stand, while the arms which interlock with the lugs are carried by the attachment, but it will be understood that any transposition of these parts will be within

the scope of my invention. Journaled 55 within these bearings are shafts 5' and 6'. The shaft 5' has fixed thereto at its ends a band wheel, as indicated at 7, and a gear 8. The shaft 6' has attached thereto at each end a gear wheel 9 adapted to mesh with 60 the gear 8 and a crank wheel 10. The wheels 9 and 10 have thereon the well known wrist-pin and pitman which is adapted to be connected with the piston rod of the pump. As this structure is well known and 65 forms no part of this invention it is not described in detail.

The means for attaching the member 4 to the lugs will now be described. This means comprises a lower pair of arms 11 70 arranged to embrace the stand 1 and to engage the lower pair of lugs 2 by means of slots 12 therein. The member 4 also has a pair of arms 13 located at the upper part thereof and embracing the stand 1. These 75 arms have hooks' thereon, indicated at 14, for engagement with the upper lugs.

The numeral 15 indicates a screw-threaded aperture in which operates a set screw 15'.

From the above description it will be 80 seen that I have invented a device that is simple in all of its parts and which is easily attached. It should be noticed that the slot 12 in the arm 11 prevents the member 4 from working downward and back and 85 forth. The upper member 13 is simply hooked around its lug and has a certain amount of play. The set screw, however, will rigidly fix the device to the standard and prevent all play. When the power 90 drive is in operation the thrust is downward and this insures the location of the member 4 securely upon the lugs, the set screw holding the same rigid.

From the foregoing disclosures it will be 95 further observed that in the manufacture and marketing of this invention it may leave the factory as a complete whole, the pump stand and the power attachment constituting such complete whole, or that the 100 pump stand may be manufactured and sold as a part of the pump without the inclusion of the power attachment which the purchaser at some later or other time may buy and use by attaching it to his stand. Therefore, in the practical marketing of the invention it will happen that some shipments 105 will be made of the complete whole, the

pump stand and the power attachment, while in other instances, these parts will be sold and shipped at different times.

While I have shown and described one embodiment of my invention it will be understood that this has been chosen for the purposes of illustration only, and that I do not desire to be limited to the details of construction shown and described, for obvious modifications will occur to a person skilled in the art.

Having thus fully described my invention, what I claim as new and desire to secure by Letters Patent, is:—

15 1. The combination, with a pump stand provided with fixed lugs projecting outwardly on opposite sides thereof, of a power attachment provided with arms embracing said stand and having portions hooked over 20 said lugs.

2. The combination, with a pump stand provided with fixed lugs projecting outwardly on opposite sides thereof, of a power attachment provided with arms embracing 25 said stand and having portions hooked over said lugs, and means for clamping the parts together.

3. In a power attachment, a body portion 30 provided with bearings, a pair of slotted arms arranged to embrace a pump stand and be attached thereto, a hook portion, and a set screw for making the engagement rigid.

4. The combination, with a pump stand provided with oppositely projecting lugs, of 35 a power attachment provided with slotted arms embracing the stand with the slots engaging the lugs, whereby the attachment is supported from the stand and movement back and forth is prevented.

40 5. The combination, with a pump stand provided with fixed lugs projecting outwardly therefrom, of a power attachment provided with a slotted member engaging certain of the lugs, a pair of hooked arms 45 embracing said stand and hooked over other of said lugs, and clamping means.

6. In a power attachment for pumps, a pump stand having lugs thereon arranged in pairs, a member adapted to support power mechanism having arms thereon arranged 50 in pairs, each pair of arms embracing the said pump stand and engaging a pair of lugs.

7. In a power attachment for pumps, a member adapted to support power mechanism, said member comprising hooks adapted to engage a pump stand, one of said hooks being slotted to prevent movement downward and back and forth, the other of said hooks arranged to allow play, and 60 a device on said member adapted to lock said member rigidly to said pump stand.

8. In a power attachment for pumps, a pump stand having spaced lugs thereon, a member adapted to support power mechanism, spaced arms on said member, one of said arms being slotted and in engagement with one of said lugs, the other of said arms having a hook in engagement with the other of said lugs, and a set screw to render the 70 engagement rigid.

9. In a power attachment for pumps, a pump stand having lugs thereon arranged in pairs, a member adapted to support power mechanism having arms thereon arranged in 75 pairs, each pair of arms embracing the said pump stand and engaging a pair of lugs, and means to render the engagement rigid.

10. In a power attachment for pumps, a pump stand having pairs of lugs spaced 80 vertically, a member adapted to support power mechanism having pairs of arms arranged vertically thereon, the lower pair of arms embracing the said pump stand and detachably engaging the lower pair of lugs, 85 the upper pair of arms embracing the pump stand and detachably engaging the upper pair of lugs, and means to render the engagement rigid.

In testimony whereof, I affix my signature. 90

PHILIP A. MYERS.
